United States Patent Office.

EBERHARD FABER, OF NEW YORK, N. Y.

Letters Patent No. 73,883, dated January 28, 1868.

IMPROVEMENT IN LEAD-PENCILS.

The Schedule referred to in these Letters Patent and making part of the same.

TO ALL WHOM IT MAY CONCERN:

Be it known that I, EBERHARD FABER, of 123 William street, New York, county and State of New York, have invented a new and useful Improvement in Pencils; and I do hereby declare that the following is a full, clear, and exact description thereof, which will enable those skilled in the art to make and use the same, reference being had to the accompanying drawing, forming part of this specification; in which drawing—

Figure 1 represents a side elevation of this invention.

Figure 2 is a longitudinal section thereof.

Similar letters indicate corresponding parts.

This invention relates to a pencil which is provided at one end with a rounded convex head, formed by dipping the pencil in a suitable enamel or compound in such a manner that on lifting the pencil out of the enamel, the drop adhering to its lower end forms the required head, and thereby not only a new and distinguishing appearance is given to my pencils, but also the end is protected against the influence of the atmosphere and of moisture, and the operation of cutting off the pencil at one end is saved.

A represents a pencil, which is made in the usual manner by inserting a piece of lead or graphite into a wooden casing. After the lead has been secured in its casing, the pencil thus formed is varnished, and finally the ends are cut off square, to give to the pencil a good appearance. Instead of varnishing the pencils I have recently adopted the plan of enamelling them, as follows: I immerse the pencils endwise in a compound of Prussian blue, linseed oil, and binoxide of manganese, or any other similar compound, known commonly by the term "japan," and having the property that the same will produce a glossy surface when baked. When a pencil is immersed into this compound and carefully withdrawn, a drop adheres to its lower end. I then bake the pencil, and after it has become dry, I repeat the operation of dipping again and again until I obtain a convex-shaped head, *a*, at the end of the pencil, as clearly shown in the drawing. By this head the pencil receives a new and distinguishing appearance; and, furthermore, by the meniscus-shaped head the end of the pencil is protected against the influence of the atmosphere, and the operation of cutting off the pencil at that end, after the same has been enamelled, is saved.

What I claim as new, and desire to secure by Letters Patent, is—

A pencil, provided with a rounded convex head, formed by dipping said pencil in a suitable compound, substantially as herein set forth.

EBERHARD FABER.
